UNITED STATES PATENT OFFICE.

FREDERICK A. HART, OF NEWARK, NEW JERSEY, ASSIGNOR TO UNDERWOOD TYPE-WRITER COMPANY, OF NEW YORK, N. Y., A CORPORATION OF DELAWARE.

TYPE-WRITING MACHINE.

1,215,306.

Specification of Letters Patent.

Patented Feb. 6, 1917.

Application filed January 3, 1916. Serial No. 69,745.

To all whom it may concern:

Be it known that I, FREDERICK A. HART, a citizen of the United States, residing in Newark, in the county of Essex and State 5 of New Jersey, have invented certain new and useful Improvements in Type-Writing Machines, of which the following is a specification.

This invention relates to sheet-collating 10 devices for typewriting machines, particularly of the variety disclosed in the patent to Jesse A. B. Smith, 1,149,794, of August 10, 1915. As shown in said patent, the sheet-collating device normally extends upwardly from the platen but may be swung 15 forwardly and downwardly about the platen axis to a substantially horizontal position, to permit the operator to arrange the work-sheets thereon, after which it may be swung 20 to its normal upright position, which is retained while the work-pieces are fed to and around the platen.

As the device is mounted on the paper carriage to travel therewith, it is desirable 25 that the framework shall be light in weight, as well as strong and rigid, and an object of the present invention is to provide an improved supporting frame possessing great strength, rigidity and lightness. For 30 this purpose, the supporting frame preferably comprises a hollow brace rod or tube mounted on the platen axle and rigidly uniting the side members of the frame, and serving as an axle or shaft for the frame.

The hollow platen of the typewriter is journaled loosely upon said rod or shaft, permitting the platen to be rotated while the frame is at rest, and also permitting the frame to swing while the platen remains at 35 rest. In order to permit the rotation of the platen either by the usual hand wheels on the platen axle or by the line-spacing mechanism, a train of gears is provided between the platen axle and platen, comprising gear 40 wheels fixed to the platen and said axle respectively, at opposite sides of one of the side members of the sheet-collating frame, and a pair of connected pinions run in mesh with said gear wheels respectively.

The work-sheets, as arranged on the collating-board, are attached to endless belts or bands, as by means of studs on said belts, which are received in corresponding apertures in the margins of the work-sheets, and 45 said belts run over the platen, being driven

thereby so that the work-sheets are advanced as the platen is rotated. The present invention provides an improved means for supporting and guiding the endless belts and the work-sheets carried thereby at the 50 upper end of the supporting frame. For this purpose, guide pulleys, over which the belts run at the upper end of said frame, are mounted on a shaft extending transversely of the frame and supported at its 55 ends in rock arms mounted at the upper ends of the side members of the frame. The shaft carrying said guide pulleys also has mounted thereon intermediate guide rollers by which the work-sheets are supported and 60 guided as they pass with the belts over said guide pulleys. The work-sheets are further guided and held in position on the belts during their passage over the guide pulleys by means of a skeleton guiding frame or 65 hood extending over said guide rollers and providing between said hood and rollers a narrow passageway through which sheets are guided. This skeleton guiding frame 70 provides a light and strong construction 75 and at the same time permits the operator to observe the position of the work-sheets thereon, and, moreover, does not cut off the light to the same extent as a closed hood or guide. Said guide pulleys are urged in an 80 upward direction by springs which maintain suitable tension on the belts, but are free to be moved against the tension of the springs as the belts are bent or curved over the platen frame when the sheet-collating 85 frame is swung forward to a horizontal position.

The side members of the sheet-collating frame preferably comprise lower portions 90 extending in an upwardly and rearwardly inclined direction from the platen axle, and upright portions extending from the upper ends of said inclined portions; the arrangement being such as to permit the main portion of the support to assume a substantially 95 horizontal position when swung forward for the assemblage of sheets thereon, and also carrying the main portion of the frame rearwardly of the platen when in its upstanding position. In order to guide the sheet-carrying bands in a path corresponding to the form of the frame, anti-friction rollers are 100 preferably mounted on the frame at the junction of said inclined and upright portions, over which rollers the bands extend, 105 110

so that the bands and sheets are guided vertically downward to said guide rollers, and thence in a forwardly inclined direction over the paper shelf to the platen.

5 Other features and advantages will hereinafter appear.

In the accompanying drawings,

Figure 1 is a perspective view of the sheet-collating mechanism mounted upon the carriage of an Underwood typewriting machine, the collating-board being in its normal upright or operative position.

Fig. 2 is a similar view with the sheet-collating board swung forward to a horizontal position to permit assembling of the work-sheets thereon.

Fig. 3 is a sectional elevation through the platen and collating frame, and also showing the gear train for rotating the platen.

20 The platen 4 is mounted for rotation by means of a platen axle 5, journaled in a platen frame 6, said axle connected with the platen through a train of gears, hereinafter described. The platen and its frame are mounted on the usual carriage, driven as by a spring drum, and having its letter-feed movements controlled by the usual mechanism, not shown. Types 7 strike against the front face of the platen to print on the work-pieces thereon. The platen axle 5 may be rotated by the usual hand wheels 8. Line-spacing mechanism for rotating the platen comprises the usual line-space lever 9 which actuates a slide carrying a pawl 10, 35 to drive the line-space ratchet wheel 11 fixed to the platen axle, said ratchet wheel being held against accidental rotation by the usual detent 12.

The sheet-collating mechanism comprises 40 a skeleton table or support, consisting of a series of parallel rods 13 mounted on a suitable supporting framework comprising upper, lower and intermediate transverse rods 14, 15 and 16, respectively. Said transverse rods are secured at their outer ends to the outer side frame bars or members 17 and 18. The side frame bars 17 and 18 are mounted at their lower ends on a tubular transverse brace rod or hollow shaft 19, (Fig. 3) the 45 latter being journaled on the platen axle 5. The frame members 17 and 18 are rigidly secured to said shaft 19 as by means of set screws 20. A very rigid, and at the same time light construction is thereby provided, 50 wherein the sheet-collating frame is free to swing about the platen axis.

The hollow platen 4 has fixed to its outer ends, platen heads 21 mounted to rotate freely on the hollow shaft 19. End plates 60 22 and 23 are secured to the outer faces of the heads 21, the plate 23 being provided with gear teeth 24, so that the plate 23 forms a gear wheel secured to the platen to rotate therewith. A gear wheel 25 fixed to the 65 platen axle 5 is connected to drive the gear

23 through gear pinions 26 and 27 meshing respectively with the gears 25 and 23, said pinions being located on opposite sides of the frame member 17 and keyed to a shaft 28 journaled in said frame member. It will be seen that the gear train just described 70 serves to rotate the platen when the axle 5 is rotated either by the hand wheels 8 or by the line-spacing mechanism. The gear wheels 23 and 25 are preferably of the same 75 diameter, so that the platen axle and platen rotate at the same angular speed.

The sheet-collating frame may be swung back and forth about the platen axle without affecting the position of the platen, the 80 pinions 26 and 27 running idly on the gears 25 and 23 respectively, as said frame swings.

When the sheet-collating frame is swung forward to the Fig. 2 position, the work-pieces may be arranged on the support or 85 table provided by the rods 13, and are retained in their collated position by means of endless belts or bands 29 and 30, each provided with a row of studs 31 adapted to enter corresponding apertures, provided in 90 the margins of the work-sheets. The belts 29, 30, run over the platen ends 21, which are each provided with a series of recesses 32 to receive correspondingly spaced teeth 33 95 projecting from the inner faces of the belts, whereby the latter are positively driven from the platen, and slipping or creeping prevented.

At the upper end of the framework the 100 belts run over pulleys or guide rolls 34 mounted on a transverse shaft 35, the latter supported in the forward ends of rock arms 36 and 37, mounted on and projecting forwardly from a rock shaft 44. The shaft 44 is journaled in the upper ends of the side 105 bars 17 and 18, the latter preferably having their upper ends offset or bent rearwardly to bring the rear faces of the guide pulleys 34 about in the plane of the collating board. The shaft 35 is urged in an upward direction and tension thereby maintained on the 110 belts by coil springs 38 mounted on rods 39 depending from said shaft and having their lower ends slidably mounted in guides 40 which also form abutments for the 115 springs 38.

Brackets 41 are mounted on the front rail of the platen frame, and are provided with curved surfaces in register with the belts, so that when the collating frame is swung down to the Fig. 2 position the belts are 120 flexed or curved over said surfaces. Each of said surfaces is provided with a groove 42 to accommodate the studs 31 and may also have a groove 43 to receive the heads 33^a of the teeth 33. The mounting of the pulley shaft 35 and pulleys 34, on the rock arms 36, 37, permits said pulleys to swing downward or toward the platen as the belts are 125 flexed, the springs 38 serving to maintain a 130

constant tension on the belts. One of the rock arms, as 36, is preferably free to swing on the shaft 44 so that the belt pulleys 34 may swing separately about the axis of the 5 rock shaft 44 as a center, whereby tension may be maintained on each belt independently of the other.

Mounted on the shaft 35 between the belt pulleys 34, are intermediate pulleys or guides 45 by which work-sheets are supported and guided as they are carried with the belts over the upper end of the collating board. A skeleton hood or guiding frame 46, positioned to overlie the work-sheets as 10 they are carried over the guide pulleys 45, comprises a series of parallel rods 47, fast at their rear ends to the rock shaft 44 and curved forwardly over the pulley shaft 35 concentrically therewith, and united at their 15 forward ends by a transverse rod 48. The form and size of this hood is such as to provide a narrow clearance or passageway for the work-pieces passing over the guides 45. Said hood being fast to the rock shaft 44, 20 rocks with said shaft and the rock arm 37 when the belt pulleys are moved inwardly as the frame is swung forward, so that the position of the hood relative to the guide pulleys remains substantially constant.

30 It will be observed that the construction of the hood 46 is at the same time light and strong, and, being entirely open, permits the operator to observe the work as it is carried over the guides beneath the said hood. The 35 open-work of the hood also reduces to a minimum the obstruction of light.

The side bars 17, 18, of the swinging frame comprise lower portions 49 inclined upwardly and rearwardly from the platen 40 axle, and substantially vertical portions 50 forming continuations of said inclined portions 49, so that when the frame is in its normal position the main portion thereof is substantially vertical. The rods 13 forming 45 the collating table are correspondingly shaped. With this construction the swinging frame is normally supported in an upright position with the collating table somewhat to the rear of the platen, and is retained in such position by its own weight. The 50 rearward swinging movement of the frame is limited by lugs 51 on the frame, engaging stop lugs 52 which may be provided on a transverse bar 53, fixed to or 55 forming part of the platen frame. The arrangement and mounting of the swinging frame and table permits the table to be brought to a substantially horizontal position when swung forward, which position is 60 convenient for the assemblage and adjustment thereon of the work-pieces. The forward movement of the frame is limited by a stop lug 54 on the platen frame in the path 65 of the frame bar 18. The lug 54 may be provided with a facing 54^a of leather or other

suitable material to form a cushion stop for the frame.

An upright frame 55 located behind the swinging frame may be rigidly connected with the platen frame, as by means of brackets 56, integral with or secured to the bar 53. This non-swinging frame is of open-work construction similar to the collating board, and when the latter is in upright position, is substantially parallel therewith, and spaced 70 therefrom a sufficient distance to provide clearance for the work-pieces, while serving to retain them in position on the belts.

A guide plate or table 57 extends in an upwardly and rearwardly inclined direction 80 from the intake side of the platen to the frame 55. The inclination of the plate 57 corresponds to that of the lower portion of the collating table, being spaced therefrom to accommodate the work-sheets. The rear 85 leads of the belts extend over anti-friction guide rollers 58 mounted in brackets 59 located at the junction of the inclined and upright parts 49, 50 of the side frame members, so that the belts are guided in a path 90 conforming to the shape of the collating table.

Supporting plates 61 extend between the pulleys 34 and the guide rollers 58 in position to form a support for the belts, particularly when the frame is swung downward to Fig. 2 position, and also prevent the belts from swinging away from the work-sheets as the latter are advanced to the platen. Said plates may be mounted as by means of side flanges 62 having ears 63 with 95 openings through which the transverse rods 14 and 16 of the frame extend. Said plates may be formed with longitudinal grooves or troughs 64 to provide clearance for the belt teeth 33.

Variations may be resorted to within the scope of the invention, and portions of the improvements may be used without others.

Having thus described my invention, I 110 claim:

1. In a typewriting machine, the combination with a roller platen; of a sheet-collating device comprising a frame mounted to swing about the platen axis from an upright position to a horizontal sheet-assembling position, said device comprising a frame having side members and a transverse brace rod concentric with the platen and rigidly uniting the side members.

2. In a typewriting machine, the combination with a rotary platen; of a sheet-collating device comprising a sheet-supporting table and a framework therefor, said framework comprising side members and a transverse member concentric with the platen and rigidly uniting said side members, the platen being rotatably mounted on said transverse member.

3. In a typewriting machine, the combination with a rotary platen; of a sheet-collat-

ing device comprising a sheet-supporting table, a framework therefor, said framework comprising side members and a transverse member concentric with the platen and rigidly uniting said side members, the platen being rotatably mounted on said transverse member, a platen axle journaled in said transverse member; and means for transmitting motion from the platen axle to the platen for rotating the latter.

4. In a typewriting machine, the combination with a rotary platen; of a sheet-collating device comprising a sheet-supporting table, a framework therefor, said framework comprising side members and a transverse member concentric with the platen and rigidly uniting said side members, the platen being rotatably mounted on said transverse member, a platen axle journaled in said transverse member; and a gear train connecting the platen axle and platen, said train comprising gears connected to the axle and the platen, respectively; pinions meshing with said gears; and a shaft to which said pinions are fixed, said last mentioned shaft journaled in one of said side members of the frame, said frame mounted to swing about the platen axis from a normal position in which it extends upwardly from the platen, to a reclining, sheet-assembling position.

5. In a typewriting machine, the combination with a rotary platen; of a sheet-collating device comprising a table or support for the arrangement of work-pieces thereon, and a supporting frame for said table, said frame mounted to swing about the platen axis, and comprising side frame bars and a transverse brace rod concentric with the platen and rigidly uniting said side bars, said rod forming bearings on which the platen is rotatably mounted between the side frame bars.

6. In a typewriting machine, the combination with a rotary platen; of a sheet-collating device comprising a table or support for the arrangement of work-pieces thereon, a supporting frame for said table, said frame mounted to swing about the platen axis, and comprising side frame bars and a transverse brace rod concentric with the platen and rigidly uniting said side bars, said rod forming bearings on which the platen is rotatably mounted between the side frame bars; a platen frame; a platen axle journaled therein, said transverse rod being hollow and journaled on said axle; and means for transmitting motion from the said axle to the platen for rotating the latter when the axle is rotated.

7. In a typewriting machine, the combination with a rotary platen; of a sheet-collating device comprising a table or support for the arrangement of work-pieces thereon, a supporting frame for said table, said

frame mounted to swing about the platen axis, and comprising side frame bars and a transverse brace rod concentric with the platen and rigidly uniting said side bars, said rod forming bearings on which the platen is rotatably mounted between the side frame bars; a platen frame; a platen axle journaled therein, said transverse rod being hollow and journaled on said axle; means for transmitting motion from the said axle to the platen for rotating the latter when the axle is rotated, said motion transmitting means comprising gears of equal diameter secured to the platen and the platen axle, respectively, on opposite sides of one of said frame bars, a shaft journaled in said last mentioned frame bar, pinions secured to said last named shaft and meshing with said gears, respectively; whereby, when the platen axle is rotated, the platen is rotated at the same angular speed, and whereby said frame may be rotated about the platen axle while the platen remains at rest.

8. In a typewriting machine, the combination with a rotary platen; of a sheet-collating device comprising a sheet-supporting table, a framework therefor, said framework comprising side members and a transverse member concentric with the platen and rigidly uniting said side members, the platen being rotatably mounted on said transverse member, and endless belts extending around the platen and driven thereby, and comprising means for engaging the work-pieces and feeding them around the platen as the latter is rotated.

9. In a typewriting machine, the combination with a rotary platen; of a work-sheet collating and feeding mechanism, comprising a work-supporting table and a framework therefor mounted to swing about the platen axis from a normal upright position forward to a work-sheet assembling position, said framework comprising side frame members, a shaft rigidly uniting said members, and on which the platen is mounted between said side members, the platen comprising heads journaled on said shaft, endless belts running over said heads and provided with a series of teeth, said heads having corresponding depressions or openings to receive said teeth, whereby the belts are positively driven when the platen is rotated, and means at the upper end of the framework for supporting and guiding said belts.

10. In a typewriting machine, the combination with a rotary platen; of a work-sheet collating and feeding mechanism, comprising a work-supporting table and a framework therefor mounted to swing about the platen axis from a normal upright position forward to a work-sheet assembling position, said framework comprising side frame members, a shaft rigidly uniting said members, and on which the platen is mount-

- ed between said side members, the platen comprising heads journaled on said shaft, endless belts running over said heads and provided with a series of teeth, said heads having corresponding depressions or openings to receive said teeth, whereby the belts are positively driven when the platen is rotated, means at the upper end of the framework for supporting and guiding said belts, 5 guide pulleys at the outer end of said table over which the belts run, a shaft carrying said pulleys, rock arms carrying said pulley shaft, and springs holding said pulleys in position to maintain tension on the belts.
- 10 11. In a typewriting machine, the combination with a rotary platen; of a sheet-collating and feeding mechanism, comprising a collating-board extending upwardly above the platen and mounted to swing forwardly to a cumbent sheet-assembling position, endless belts driven by the platen and extending upwardly therefrom in position to support the side margins of work-sheets arranged on said board, means on said belts 20 for engaging the sheets and causing them to be advanced with the belts, guide pulleys at the upper end of said board, over which the belts are guided, a transverse pulley shaft on which said pulleys are mounted, rock arms carrying said pulley shaft, and springs to urge the said shaft in a direction to maintain tension on the belts.
- 25 12. In a typewriting machine, the combination with a rotary platen; of a sheet-collating and feeding mechanism, comprising a collating-board extending upwardly above the platen and mounted to swing forwardly to a cumbent sheet-assembling position, endless belts driven by the platen and extending upwardly therefrom in position to support the side margins of work-sheets arranged on said board, means on said belts 30 for engaging the sheets and causing them to be advanced with the belts, guide pulleys at the upper end of said board, over which the belts are guided, a transverse pulley shaft on which said pulleys are mounted, rock arms carrying said pulley shaft, and springs to urge the said shaft in a direction to maintain tension on the belts.
- 35 13. In a typewriting machine, the combination with a rotary platen; of a sheet-collating and feeding mechanism, comprising a collating-board extending upwardly above the platen and mounted to swing forwardly to a cumbent sheet-assembling position, endless belts driven by the platen and extending upwardly therefrom in position to support the side margins of work-sheets arranged on said board, means on said belts 40 for engaging the sheets and causing them to be advanced with the belts, guide pulleys at the upper end of said board, over which the belts are guided, a transverse pulley shaft on which said pulleys are mounted, rock arms carrying said pulley shaft, and springs to urge the said shaft in a direction to maintain tension on the belts, and intermediate 45 pulleys or guides on said pulley shaft to support the work-sheets as they are fed around said pulleys.
- 50 14. In a typewriting machine, the combination with a rotary platen; of a sheet-collating and feeding mechanism, comprising a collating-board extending upwardly above the platen and mounted to swing forwardly to a cumbent sheet-assembling position, endless belts driven by the platen and extending upwardly therefrom in position to support the side margins of work-sheets arranged on said board, means on said belts 55 for engaging the sheets and causing them to be advanced with the belts, guide pulleys at the upper end of said board, over which the belts are guided, a transverse pulley shaft on which said pulleys are mounted, rock arms carrying said pulley shaft, and springs to urge the said shaft in a direction to maintain tension on the belts, and a skeleton hood or guide located over said pulley shaft, concentric therewith, in position to retain the work-sheets on the belts as they are carried around said pulleys.
- 60 15. In a typewriting machine, the combination with a rotary platen; of sheet feeding mechanism, comprising a supporting frame extending upwardly above the platen and mounted to swing forward, a rock shaft mounted in the upper end of said frame and 65 extending transversely between the side members of said frame, rock arms mounted on said rock shaft, a pulley shaft carried on said arms, pulleys on said shaft, endless belts running over said pulleys and extending downwardly therefrom and driven by the platen, springs maintaining an upward pressure on the pulley shaft and thereby maintaining tension on the belts, and means forming supporting surfaces over which the belts are flexed when the frame is swung forward, said pulley shaft yieldable under the tension of the belts as they are flexed.
- 70 16. In a typewriting machine, the combination with a rotary platen; of sheet feeding mechanism, comprising a supporting frame extending upwardly above the platen and mounted to swing forward, a rock shaft mounted in the upper end of said frame and 75 extending transversely between the side members of said frame, rock arms mounted on said rock shaft, a pulley shaft carried on said arms, pulleys on said shaft, endless belts running over said pulleys and extend-

ing downwardly therefrom and driven by the platen, springs maintaining an upward pressure on the pulley shaft and thereby maintaining tension on the belts, means 5 forming supporting surfaces over which the belts are flexed when the frame is swung forward, said pulley shaft yieldable under the tension of the belts as they are flexed, and a hood or guide carried by said rock 10 shaft and arranged substantially concentric with the pulley shaft to guide the work-sheets as they are carried with the belts around the pulleys, one of said rock arms being fixed to said rock shaft to cause the 15 latter to rock and swing said hood therewith as the pulleys are drawn inwardly by the flexing of the belts.

17. In a typewriting machine, the combination with a rotary platen; of sheet feeding mechanism comprising a supporting frame extending upwardly above the platen and mounted to swing forward, a rock shaft mounted in the upper end of said frame and extending transversely between the side 25 members of said frame, rock arms mounted on said rock shaft, a pulley shaft carried on said arms, pulleys on said shaft, endless belts running over said pulleys and extending downwardly therefrom and driven by the 30 platen, springs maintaining an upward pressure on the pulley shaft and thereby maintaining tension on the belts, means forming supporting surfaces over which the belts are flexed when the frame is swung forward, 35 said pulley shaft yieldable under the tension of the belts as they are flexed, and a hood or guide carried by said rock shaft and arranged substantially concentric with the pulley shaft to guide the work-sheets as they 40 are carried with the belts around the pulleys, one of said rock arms being fixed to said rock shaft and the other of said rock arms being rotatably mounted on the rock shaft to permit tension to be maintained on 45 each belt independently of the other.

18. In a typewriting machine, the combination with a rotary platen; of means for supporting and feeding work-sheets to the platen, comprising a frame normally extending upwardly above the platen and mounted to swing forward to work-sheet receiving position, endless belts driven by the platen and extending upwardly therefrom to the upper end of said frame, belt pulleys at the 50 upper end of said frame, over which said belts run, a pulley shaft carrying said pulleys, rock arms carrying the pulley shaft, guides on said pulley shaft intermediate the belt pulleys, by which the work-sheets are 55 guided and supported as they are carried with the belts around said pulleys, and a skeleton hood extending over said pulleys and guides in position to retain the work- 60

sheets on said belts as they are carried over said pulleys.

19. In a typewriting machine, the combination with a rotary platen; of a sheet-collating device comprising a sheet-supporting table, a framework therefor, said framework comprising side members and a transverse member concentric with the platen and rigidly uniting said side members, the platen being rotatably mounted on said transverse member, a platen axle journaled in said transverse member; and a gear train connecting the platen axle and platen, said train comprising gears connected to the axle and the platen, respectively, pinions meshing with said gears, and a shaft to which said pinions are fixed.

20. In a typewriting machine, the combination with a rotary platen; of endless work-sheet carrying belts driven by the platen; a supporting frame for said belts comprising an upwardly and rearwardly inclined portion, and an upright portion forming a continuation of said inclined portion, guide pulleys at the upper end of the frame, over which the belts extend; and anti-friction guide rolls at the lower end of said upright portion of the frame, over which the belts are guided; a sheet-collating table consisting of openwork, and lying substantially in the plane of the leads of the belt between said pulleys and anti-friction rolls; and supporting plates extending between said pulleys and anti-friction rolls in front of and close to said leads of the belt.

21. In a typewriting machine, the combination with a rotary platen; of work-sheet 100 supporting and feeding mechanism comprising a sheet-collating table having an inclined portion extending upwardly and rearwardly above the platen, and an upright portion forming a continuation of said inclined portion, said table consisting of an open wire-work construction, endless conveyers driven by the platen, and located laterally beyond the sides of said table, said table and conveyers arranged to swing forward and 110 downward to sheet-assembling position, means for supporting and guiding the conveyers so that one lead of each belt extends about in the plane of said table, and supporting plates underlying said leads and supporting them in position to receive the side margins of work-sheets arranged on 115 said table, and means on said belts for attaching the work-sheets thereto and causing them to be advanced with the belts to the 120 platen when the latter is rotated.
